UNITED STATES PATENT OFFICE

W. R. POMEROY, OF MILLERSBURG, OHIO.

IMPROVEMENT IN CARTRIDGES.

Specification forming part of Letters Patent No. 36,108, dated August 5, 1862.

To all whom it may concern:

Be it known that I, W. R. POMEROY, of Millersburg, in the county of Holmes, in the State of Ohio, have invented a new and Improved Mode of Constructing Cartridges; and I do hereby declare that the following is a full and exact description thereof, reference being had to the accompanying drawings, and to the letters of reference marked thereon.

The nature of my invention consists in first constructing the cartridge upon the old plan, except that the wrapper of the cartridge is made first of sufficient length to contain the ball and charge of powder; then an outside wrapper is secured firmly around and independent of the aforesaid wrapper, letting the said outside wrapper project over and past the end of the inside wrapper, so as to admit of being secured by twisting or folding, as other cartridges.

To enable others skilled in the art to make and use my invention, I will proceed to describe its construction and application.

I construct my cartridge upon the original plan, except that the top is cut off immediately

above the powder, at A, Figure 1; then an outside wrapper, C, Fig. 2, is secured firmly and independently around the body of the cartridge B, Fig. 1, having it project over and past the end A of said cartridge, to admit of being secured by twisting or folding, as at D, Fig. 2.

To use this cartridge, the operator takes hold of the end which contains the ball, with his hand, and places the top between his teeth, when the wrapper C is readily removed, thereby exposing the powder.

What I claim as my invention, and desire to secure by Letters Patent, is—

The arrangement of the cartridge in such a manner as to obviate the necessity of biting, as heretofore, using for that purpose the wrapper C, arranged in the manner and for the purpose described.

W. R. POMEROY.
